ATTORNEY

UNITED STATES PATENT OFFICE.

CHARLES CLEVES, OF OMAHA, NEBRASKA.

RUBBER SHOE.

SPECIFICATION forming part of Letters Patent No. 311,473, dated February 3, 1885.

Application filed November 8, 1884. (No model.)

To all whom it may concern:

Be it known that I, CHARLES CLEVES, a citizen of the United States, residing at Omaha, in the county of Douglas and State of Nebraska, have invented certain new and useful Improvements in Rubber Shoes; and I do hereby declare that the following is a full, clear, and exact description of the invention, which will enable others skilled in the art to 10 which it appertains to make and use the same.

Heretofore rubber shoes have been so constructed that in use the necessary strain upon the top or mouth in being put on and taken off the foot tears the material and renders the 15 shoe useless.

The object of my invention is to so protect and strengthen the edge of the material at the mouth of the shoe as to prevent its being so torn, which object I attain by means of a flat 20 metal chain laid into the border or welt around the mouth of the shoe, as illustrated in the accompanying drawing, in which the figure represents an elastic rubber shoe, and the letters *a* and *b* an exposed section of the chain in the 25 welt around the mouth of the shoe.

This chain is made of links of two different

shapes, one (that represented in the drawing by the letter *a*) being constructed of sheet metal, and the other, *b*, of round metal or wire, which links are elongated and placed in the 30 chain alternately, thus forming a continuous flat chain, capable of shortening and lengthening as the mouth of the shoe is expanded or relaxed. The length of the chain is adapted to the size of the mouth of the shoe, but only 35 so long as to permit a medium expansion of the rubber and prevent its tearing.

To prevent the rubber from penetrating the links of the chain during manufacture, either the lining of the shoe will be turned over the 40 chain, or it will be covered by a thin fabric before putting it in place.

What I claim as my invention, and desire to secure by Letters Patent, is—

A rubber shoe provided with a metallic 45 chain inclosed around the mouth or foot opening of the shoe, all substantially as and for the purpose set forth.

CHARLES CLEVES.
